UNITED STATES PATENT OFFICE.

DURBIN RICHARDSON AND CHARLES N. JACOBY, OF ROCHESTER, NEW YORK,
ASSIGNORS TO RICHARDSON CORPORATION, OF ROCHESTER, NEW YORK, A
CORPORATION OF NEW YORK.

DESIGN FOR A BEVERAGE-DISPENSING APPARATUS.

54,363.

Specification for Design.

Patented Feb. 3, 1920.

Application filed November 5, 1917. Serial No. 200,451. Term of patent 14 years.

To all whom it may concern:

Be it known that we, DURBIN RICHARDSON and CHARLES N. JACOBY, both of Rochester, in the county of Monroe and State of New York, have invented a new, original, and ornamental Design for a Beverage-Dispensing Apparatus, of which the accompanying drawings are representations.

Figure 1 is a front elevation, and
Fig. 2 is a side elevation.

We claim:

The ornamental design for a beverage dispensing apparatus, as herein shown.

DURBIN RICHARDSON.
CHARLES N. JACOBY.
